UNITED STATES PATENT OFFICE

ARTHUR L. FOSTER, OF MIDDLETOWN, NEW JERSEY, ASSIGNOR TO MANIFOLD SUPPLIES COMPANY, OF BROOKLYN, NEW YORK, A CORPORATION OF NEW YORK

INK RIBBON WINDING AND MEASURING MECHANISM

Application filed July 7, 1927. Serial No. 203,960.

My invention relates to mechanism which may be advantageously employed in winding ink ribbons upon metal spools adapted for detachable connection with typewriting, billing, adding and similar machines. Different lengths of such ribbons are required for different forms of such machines, and my invention provides means for adjustably predetermining the length of the ribbons thus wound and automatically indicating when the desired length is wound upon each spool, by stopping the winding operation. Moreover, it is necessary, commercially, that the ribbons thus wound shall be without defects; and my invention includes means for detecting such defects and automatically stopping the winding mechanism when a defect is thus detected in a ribbon being wound.

The form of my invention hereinafter described includes a winding shaft operatively connected with an electric motor, and means enabling the operator to instantly rigidly connect such a spool with said shaft and instantaneously disconnect the same; means arranged to stop the winding mechanism, means which may be manually adjusted and set to predetermine and measure the length of each commercially acceptable ribbon which may be wound before the stop mechanism is caused to operate; and means to automatically operate said stop mechanism upon presentation of a defect in the ribbon being wound. In that form of my invention, the means for variably predetermining the length of ribbon to be wound comprises an endless chain, of variable circumferential length, including a stop link which is operative to release the stop mechanism, at intervals determined by the length of said chain, which bears a definite relation to the length of the ribbon wound by said shaft. The defect detecting mechanism for automatically operating the stop mechanism, includes a movable ribbon gauge carried by a lever, which is arranged to permit the passage of normal ribbon through said gauge without movement of the latter, but to be tilted by engagement of an abnormal defective portion of the ribbon with said gauge, to thus release the stop mechanism; whereby the winding operation

is stopped upon presentation of a defective portion of ribbon at said gauge; regardless of the length of ribbon which has been wound.

My invention includes the various novel features of construction and arrangement hereinafter more definitely specified.

In said drawings: Fig. I is a perspective view of mechanism conveniently embodying my invention as seen from the right hand front corner thereof.

Fig. II is a perspective view of said mechanism, as seen from the left hand front corner thereof.

Fig. III is a fragmentary perspective view of parts of the stop mechanism.

Fig. IV is a fragmentary perspective view of the ribbon gauge and the stop mechanism tripping device operatively connected therewith.

Fig. V is an end view of a metal spool for the ink ribbon, such as is indicated in Figs. I and II.

In said figures, the ink ribbon 1 is supplied by the manufacturer in rolls 2, which are successively supported upon the shaft 3 in the stand 4 resting upon the table 5. Said ribbon passes from said roll 2 around the vertical guide roller 6 which is journaled in the angularly adjustable standard 7 upon said table. Said ribbon 1 passes from said roller 6 over the horizontal guide roller 8, which is journaled in the stationary frame 9, and thence around the measuring roller 11 which is also journaled in said frame 9. From said measuring roller 11, the ribbon 1 passes over the guide roller 12 and thence through the ribbon gauge 14, and around the guide bar 15, which is supported in the frame 24. Said ribbon extends between the adjustable stop collars 16 which are clamped on said bar 15 by respective set screws 17. From said bar 15, said ribbon 1 passes to the detachable metal spool 19 upon which it is to be wound. As shown in Fig. V; said spool has the axial opening 20 for the winding shaft 21, and the eccentric opening 22 for the crank pin 23 which is carried by said shaft 21. Said shaft 21 is journaled in the frame 24, surrounded by the stationary crown cam 25, and is arranged to be rotated by the cone clutch pulley 101

26; which latter is driven by the belt 27 extending from the pulley 28 on the shaft 29 of the electric motor 30, but is axially movable by turning movement of the cam 31 against said cam 25.

5 Said measuring roller is rotated, in the direction of the arrows marked thereon in Figs. I and II, by frictional engagement with said ribbon 1, and such motion thereof is caused 10 to operate stop mechanism for stopping the winding operation when a predetermined and adjustably variable length of ribbon has been wound on the spool, by providing said measuring roller with the gear 32, in 15 coaxial relation therewith and in engagement with the gear 33 which is journaled on the stud 34 in said frame 9. Said gear 33 carries the gear 35 which engages the gear 36 on the chain shaft 37. Said shaft 37 20 is journaled in said frame 9, and provided with the chain driving wheel 39; so that the latter is turned in definite relation to the rotary movement of said measuring roller 11, but at a very much slower rate.

25 Said chain driving wheel 39 is engaged by the endless pattern chain 40 which has the high stop link 41 by which the stop mechanism is automatically released, as hereinafter described. Said chain 40 may be made of any 30 circumferential length desired, corresponding with the length of ribbon to be wound upon the spool 19 and such different circumferential length chains are arranged to be supported in their operative engagement 35 with the chain driving wheel 39, by means of the idle chain wheel 43 which is provided with means adjustable to support it at different distances from said driving chain wheel 39. As best shown in Fig. I; such 40 adjustable supporting means conveniently includes the lever 45 which is provided with the stud shaft 46 upon which said idle chain wheel 43 is journaled. Said lever 45 is conveniently mounted upon the fulcrum shaft 48 in the bearing 49 secured to said table 5 and may be secured in any desired angular position, by the set screw 50.

50 Said ribbon gauge 14 is conveniently formed of parallel plates which are held by the set screw 52 in such spaced relation as to permit the passage of a normal ribbon 1 between them, without movement of said gauge; but any knot, torn portion, or other defect in said ribbon, increasing its normal thickness, causes the ribbon to move said gauge in the direction of its traverse. Said gauge is conveniently mounted upon the gauge lever arm 54 rigidly connected with the rock shaft 55 and normally held in the position shown, by the spring 56 extending therefrom to said frame 9, as shown in Fig. I. As shown in Fig. IV, said rock shaft 55 carries the trip lever arm 57 which is a crank having, pivotally connected therewith at 58, the trip slide 59 which is fitted to slide upon the standard 60

against which it is resiliently held by the spring 61 which extends to the stud 62 on the base plate 63 of the frame 24. The construction and arrangement described are such that when said gauge 14 is moved by the ribbon 1 70 as a consequence of a defective portion of such ribbon being caught at said gauge; said shaft 55 is rocked to thrust the slide 59 up the standard 60 and lift the latch 64 which has a hook end normally held, in the position indicated in dotted lines in Fig. I, with said hook overhanging the right hand side of the pin 65; in which position it is normally detained by the spring 66 extending from said latch 64 to said stud 62, as indicated in Fig. I. The full lines in Fig. I indicate the stopped position of said latch 64, which is pivoted at 68 upon the starting handle 69. Said handle is fulcrumed on said winding shaft 21; and the spring 70 tends to tilt it in the direction of the arrow in Fig. I, but is normally restrained by the engagement of said latch 64 with said pin 65. When said latch is disengaged from said pin, such tilting movement turns said cam 31 and axially disengages the cone 71 of said pulley 26 from the hollow conical clutch head 72 on said shaft 21, which is normally frictionally engaged therewith; and also applies the brake 73 to stop the rotation of said shaft 21. Said clutch cone 71 is axially 90 thrust into frictional engagement with the clutch head 72 on said shaft 21 by the coaction of said stationary cam 25 and rotary cam 31, shown in Figs. II and III; when said cam 31 is turned clockwise in said figures. Said cam is thus turned, to start the machine, by manually pressing down the left hand end of the lever which is marked 69 in Fig. I; against the stress of the spring 70, and to a sufficient extent to engage the latch 64 with 95 said pin 65. Said latch 64 is snapped down over said pin 65 by the spring 66 when said depressing movement has reached the proper extent. Said clutch members remain thus engaged until said latch 66 is tripped up at its right hand end in Fig. I, permitting the stress of the spring 70 to reverse the rotary movement of said cam 31 with respect to the stationary cam 25, accompanied by the sliding movement of the latch 64 toward the left in 100 Fig. I to the position shown in that figure, which, as above noted, is the stopped position. Said brake 73 is a semicircular yoke arranged to press the shoe 74, of leather or other friction material, against said head 72, and is provided with the vertical shank 75 which is normally pressed upward by the spring 76 bearing upon the cross head 77, one end of which is pivoted in the frame standard 24 and the other end of which is pivoted in the hanger 78 105 of said starting lever 69. Said hanger is pivotally connected to said lever 69 in eccentric relation to the fulcrum of said starting lever which is the axis of said winding shaft 21. 110

115

120

125

130

The starting lever 69 rests upon the top of the lever 80 which is fulcrumed in the standard 81 which is fixed in the base plate 63 immediately adjoining the standard 60. The 5 arm 82 of said lever 80 pivotally engages the measuring roller brake lever 83 which is fulcrumed at 84 on said frame 9 and carries the brake shoe 85 which is adapted to press upon the end of the measuring roller 11, but is normally held away from the latter by the spring 87, which latter is attached at its lower end to said base plate 63 and at its upper end to 10 said brake lever 83. Therefore, when said spring 70 is permitted to contract by the release of said latch 64 from the pin 65 in the standard 60; it also overcomes the tension of the spring 87 and applies the brake shoe 85 to stop the movement of the measuring roller 11.

20 Of course, such stoppage of the winding operation and of the consequent rotation of the measuring roller also stops the movement of said pattern chain 40. However, the high link 41 on said chain is also effective to stop the winding operation by the mechanism above described as operatively connected with the ribbon gauge 14; the movement of said high link, by the rotation of the measuring roller 11, causing it to uplift said latch 64 by 25 encountering the end thereof, in the position indicated in dotted lines in Fig. I, to release said latch 64 and permit it to pass to the position shown in full lines in Fig. I, which is the stopped position.

35 Operation of the winding mechanism may be resumed, by pressing down upon the handle 69 (against the tension of said spring 70,) which slides the latch 64 to the right in Fig. I and permits its re-engagement with the pin 40 65 by the tension of its spring 66.

In the normal operation of said mechanism; with the mechanism in the stopped position shown; the ribbon 1 having been wound upon the spool 19 to the predetermined length determined by the length of said chain 40; said ribbon is manually cut between said spool and said guide bar 15 and the end thereof provided with an attaching clip for connection with the machine in which said spool and 45 ribbon are to be used and, thereupon, the filled spool 19 is removed and an empty spool substituted. The cut end of the ribbon 1 which remains extending through the ribbon gauge 14 is re-drawn around the guide bar 50 15 provided with an eyelet or other fastening means, and connected to the empty spool upon the winding shaft 21. Thereupon, the operator presses down upon the handle 69 and thus releases and resets the stop mechanism with the latch 64 in engagement with the pin 65; thus contemporaneously releasing both of the brakes 73 and 85 so that the winding operation of the shaft 21 is resumed; to be again stopped after a predetermined 60 65 length of ribbon is wound; the length of

which is determined by the length of the chain 40; or to be stopped at any period in the winding operation when a defective portion of the ribbon is presented at the gauge 14. The operation is thus repeated. There may be thus 70 successively wound upon individual spools, ribbons which are all of the same length, determined by the length of the chain 40; but, as above contemplated, chains of different lengths may be interchangeably connected 75 with and supported by said chain wheels 39 and 43.

Therefore, I do not desire to limit myself to the precise details of construction and arrangement herein set forth, as it is obvious 80 that various modifications may be made therein without departing from the essential features of my invention, as defined in the appended claims.

I claim:

1. In ink ribbon winding and measuring mechanism; the combination with a winding shaft; of a ribbon spool; a clutch carried by said shaft; means on said shaft arranged to detachably engage and turn the ribbon spool; a motor arranged to turn said shaft; a chain driving wheel; a roller arranged to be traversed and turned by the ribbon being wound; and means operatively connecting said roller with said chain driving wheel; whereby said chain driving wheel is arranged to be driven by power from said motor, conveyed by the ribbon being wound; an idle chain wheel; an endless chain supported by said chain wheels; and means, including a lever linkage and a stop link in said chain, arranged to stop the winding operation of said shaft, at intervals determined by the circumferential length of said chain, and thereby determine the length of ribbon wound by said spool.

2. In ink ribbon winding and measuring mechanism; the combination with a winding shaft; of a ribbon spool; a clutch carried by said shaft; means on said shaft arranged to detachably engage and turn the ribbon spool; a motor arranged to turn said shaft; a chain driving wheel; a roller arranged to be traversed and turned by the ribbon being wound; and means operatively connecting said roller with said driving wheel; whereby said chain driving wheel is arranged to be driven by power from said motor, conveyed by the ribbon being wound; an idle chain wheel; means adjustable to support said idle chain wheel at different distances from said driving wheel; an endless chain, of a length determined by the length of ribbon to be wound, supported by said chain wheels; means, including a lever linkage and a stop link in said chain, arranged to stop the winding operation of said shaft, at intervals determined by the circumferential length of said chain, and thereby variably determine the length of ribbon wound by said spool.

3. In ink ribbon winding and measuring

mechanism; the combination with a winding shaft; of a ribbon spool; a clutch carried by said shaft; means on said shaft arranged to detachably engage and turn the ribbon spool; 5 a motor arranged to turn said shaft; a chain driving wheel arranged to be driven by power from said motor, conveyed by the ribbon being wound; a measuring roller rigidly connected with said driving wheel, and arranged to be traversed by the ribbon; an idle chain wheel; 10 an endless chain supported by said chain wheels; means, including a lever linkage and a stop link in said chain, arranged to stop the winding operation of said shaft, at intervals 15 determined by the circumferential length of said chain, and thereby determine the length of ribbon wound by said spool.

4. In ink ribbon winding and measuring mechanism; the combination with a winding shaft; of a ribbon spool; a clutch carried by 20 said shaft; means on said shaft arranged to detachably engage and turn the ribbon spool; a motor arranged to turn said shaft; a chain driving wheel; a roller arranged to be traversed and turned by the ribbon being wound; and means operatively connecting said roller with said chain driving wheel; whereby said chain driving wheel is arranged to be driven by power from said motor, conveyed by the 25 ribbon being wound; an idle chain wheel; an endless chain supported by said chain wheels; means, including a lever linkage and a stop link in said chain, arranged to stop the winding operation of said shaft, at intervals 30 determined by the circumferential length of said chain, and thereby determine the length of ribbon wound by said spool; a movable ribbon gauge permitting passage 35 of a normal ribbon without movement of said gauge, but movable by engagement with an abnormal portion of the ribbon; and means operatively connecting said gauge with the winding shaft 40 stop mechanism; whereby the winding operation is stopped upon presentation of a defective portion of ribbon at said gauge. 45

5. Mechanism as in claim 1; including a latch normally restraining the winding shaft stop mechanism from operating until said latch is released; said link being adapted to 50 move said latch, to release the latter, at predetermined intervals.

6. Mechanism as in claim 4; including a latch normally restraining the winding shaft stop mechanism from operating until 55 said latch is released; said link being adapted to move said latch, to release the latter, at predetermined intervals; a rock shaft having a gauge lever arm supporting said gauge; and a trip lever arm on said rock shaft, arranged to release said latch when said gauge is moved by a defective ribbon.

7. In ink ribbon winding and measuring mechanism, the combination with a winding shaft; of a ribbon spool; a clutch carried by 60 said shaft; means on said shaft arranged to

detachably engage and turn the ribbon spool; a motor arranged to turn said shaft; a measuring roller arranged to be traversed and turned by said ribbon, as the latter is wound upon said spool; a pattern chain driving wheel rigidly connected with said measuring roller; an idle chain wheel; an endless pattern chain supported by said chain wheels; means, including a lever linkage and a high link in said chain, arranged to stop the winding operation of said shaft, at intervals 70 determined by the circumferential length of said chain, and thereby determine the length of ribbon wound by said spool. 75

8. In ink ribbon winding and measuring mechanism, the combination with a winding shaft; of a ribbon spool; a clutch carried by said shaft; means on said shaft arranged to detachably engage and turn the ribbon spool; a motor arranged to turn said shaft; a measuring roller arranged to be traversed and turned by said ribbon, as the latter is wound upon said spool; a pattern chain driving wheel rigidly connected with said measuring roller; an idle chain wheel; an endless pattern chain supported by said chain wheels; means, including a lever linkage and a high link in said chain, arranged to stop the winding operation of said shaft, at intervals 80 determined by the circumferential length of said chain, and thereby determine the length of ribbon wound by said spool; a movable ribbon gauge permitting passage 85 of a normal ribbon without movement of said gauge, but movable by engagement with an abnormal portion of the ribbon; and means operatively connecting said gauge with the winding shaft stop mechanism; whereby the winding operation is stopped upon presentation of a defective portion of 90 ribbon at said gauge. 95

9. In ink ribbon winding and measuring mechanism; the combination with a winding shaft; of a ribbon spool; a clutch carried by said shaft; means on said shaft arranged to detachably engage and turn the ribbon spool; a measuring roller arranged to be turned by the ribbon on its way to said spool; an endless chain, including a stop element; and stop mechanism, arranged to be operated by the 100 movement of said chain. 110

10. In ink ribbon winding and measuring mechanism; the combination with a winding shaft; of a ribbon spool; a clutch carried by said shaft; means on said shaft arranged to detachably engage and turn the ribbon spool; a measuring roller arranged to be turned by the ribbon on its way to said spool; an endless chain, including a stop element; stop mechanism, including a lever linkage arranged to 115 be operated by the movement of said chain; a brake for said shaft; and brake applying means including a lever arranged to be operated by said chain contemporaneously with the operation of said stop mechanism. 120 125 130

11. In ink ribbon winding and measuring mechanism; the combination with a winding shaft; of a ribbon spool; a clutch carried by said shaft; means on said shaft arranged to detachably engage and turn the ribbon spool; a measuring roller arranged to be turned by the ribbon on its way to said spool; an endless chain, including a stop element; stop mechanism, including a lever linkage arranged to be operated by the movement of said chain; a brake for said measuring roller; and brake applying means including a lever arranged to be operated by said chain contemporaneously with the operation of said stop mechanism.

12. In ink ribbon winding and measuring mechanism; the combination with a winding shaft; of a ribbon spool; a clutch carried by said shaft; means on said shaft arranged to detachably engage and turn the ribbon spool; a measuring roller arranged to be turned by the ribbon on its way to said spool; an endless chain, including a stop element; stop mechanism, including a lever linkage arranged to be operated by the movement of said chain; separate brakes respectively for said shaft and said measuring roller; and brake applying means including a lever arranged to be operated by said chain contemporaneously with the operation of said stop mechanism.

13. In ink ribbon winding and measuring mechanism; the combination with a winding shaft; of a ribbon spool; a clutch carried by said shaft; means on said shaft arranged to detachably engage and turn the ribbon spool; a measuring roller arranged to be turned by the ribbon on its way to said spool; an endless chain, including a stop element; stop mechanism arranged to be operated by the movement of said chain, at intervals predetermined by the circumferential length of said chain; and a ribbon gauge mechanism, including a lever and a spring arranged to be operated by a defective portion of the ribbon, on its way to said spool and to operate said stop mechanism independently of said chain.

14. In ink ribbon winding and measuring mechanism; the combination with a measuring roller arranged to be turned by the ribbon to be measured; a pattern chain, including a stop element, means operatively connecting said chain with said measuring roller; stop mechanism including a lever linkage constructed and arranged to be actuated by said chain; whereby the operation of said mechanism is stopped at intervals predetermined by the circumferential length of said chain; a brake for said measuring roller; and brake applying means including a lever arranged to be operated by said chain, contemporaneously with the operation of said stop mechanism, to arrest said measuring roller.

15. In ink ribbon winding mechanism; the combination with a winding shaft; of a ribbon spool; a clutch carried by said shaft; means on said shaft arranged to detachably engage and turn the ribbon spool; an endless pattern chain, including a stop element, driving means, whereby said chain is arranged to be driven in correspondence with rotation of said winding shaft; a brake, for said winding shaft; and brake applying means including a lever arranged to be operated by said pattern chain, to stop the rotation of said shaft, at intervals predetermined by the circumferential length of said chain.

In testimony whereof, I have hereunto signed my name at Brooklyn, New York, this 27th day of June, 1927.

ARTHUR L. FOSTER.
